UNITED STATES PATENT OFFICE.

NELSON CLEMENT, DECEASED, LATE OF CHICAGO, ILLINOIS, BY MARGARET CLEMENT,
ADMINISTRATRIX, OF CHICAGO, ILLINOIS.

BED.

1,071,396.

Specification of Letters Patent. Patented Aug. 26, 1913.

Application filed August 5, 1912. Serial No. 713,430.

To all whom it may concern:

Be it known that NELSON CLEMENT, late a citizen of the United States and a resident of the city of Chicago, Illinois, did invent 5 certain new and useful Improvements in Beds; and I, as administratrix of the estate of the said NELSON CLEMENT, do hereby declare that the following description of his said invention, taken in connection with the 10 accompanying sheets of drawings, forms a full, clear, and exact specification, which will enable others skilled in the art to which it appertains to make and use the same.

This invention has general reference to 15 improvements in beds, particularly collapsible beds, and it consists, essentially, in the novel and peculiar combination of parts, and details of construction, as hereinafter first fully set forth and described, and then 20 pointed out in the claims.

In the drawings already referred to, Figure 1 is a perspective view of my newly invented bed. Fig. 2 is a transverse, vertical section in line 0 0 of Fig. 1, taken in the 25 direction of the arrow pointers. Fig. 3 is a similar section in the direction of the arrow pointers in line 1 1 of Fig. 1. Fig. 4 is a perspective view of the straining or stretching frame collapsed, with the bed 30 fabric folded over the same. Fig. 5 is a transverse section taken in the direction of the arrow pointers in line 2 2 of Fig. 4. Fig. 6 is an outline elevation of means for 35 vibrating the bed when it is used as a child's cradle.

Like parts are designated by corresponding letters or characters of reference in all the figures of the drawings.

The object of this invention is the production 40 of a bed of the collapsible type which may be folded together to occupy but little space; a bed which is absolutely rigid when set up, and, which, when produced in smaller sizes will form a light, compact, 45 and convenient child's cradle.

Another object is the production of an article of this class of high sanitary qualities, because of the ease with which the component parts may be taken apart and 50 cleaned.

Briefly this invention comprises a bed bottom and sides formed from an integral piece of flexible or fibrous material, such as rubber, canvas, or other like materials, the lon-

gitudinal edges of which are suspended 55 from longitudinal bars spaced a suitable or proper distance apart, and the sides and the bottom of which are stretched to a proper degree of tension for occupancy by means of an independent stretching frame engaging 60 the supporting posts of the bed, and capable of being held in position, irrespective of the weight exerted by the occupant thereof.

For a better understanding of this invention, attention is first directed to Fig. 1, in 65 which A is the bed bottom, as it were, formed integrally with the sides B and C. The upper, longitudinal edges of these sides are suspended from longitudinal supporting bars b and c by means of a continuous 70 "bight" or hem "a" formed along both of said edges, through which said bars b and c are passed, it being understood, however, that any other means of fastening may be employed if desired. The free ends of 75 aforesaid supporting bar c are passed through apertures located at or near the upper ends of upstanding, bed corner posts 1 and 2, which apertures are sufficiently larger than the ends of the said supporting 80 bar c to permit a free entrance and removal therefrom. The free ends of the bar b are supported in similar apertures located at or near the upper ends of like bed corner posts 3 and 4, of which the corner post 3 is located 85 opposite post 1, in the same manner that post 4 is positioned opposite post 2, so that the opposing corner posts 1 and 3 and 2 and 4 form a rectangle in plan.

Between the corner posts 1 and 3, which I 90 will term the head end of the bed, are movably fastened top and bottom head braces 5 and 6, respectively, of the bed bottom stretching frame D, Fig. 4, above mentioned. Between the foot corner posts 2 and 4 are 95 similar movably fastened top and bottom braces 7 and 8, which are also a part of said stretching frame D.

The corner posts 1 and 3 of the head of the bed are held in rigid position with 100 respect to each other by means of a long rod 9 passing transversely through the said corner posts and having at one end an enlarged knurled head 10, which bears against the outer surface of the post 3, while its 105 opposite end, which is properly threaded, screws into a nut 11, embedded in the outer face of the post 1. Foot corner posts 2 and

- 4 are likewise held rigidly together by means of a threaded rod 9^a, knurled head 10^a, and nut 11^a.
- Connecting the top head and foot braces 5 and 7 at points closely adjacent to the inner faces of the head and foot posts 1 and 2, is a bed side-straining rod 12, which rod is preferably round and is rigidly attached to said braces by glue and nails. The opposite ends of said braces 5 and 7 are connected together in a similar manner by a round side-straining rod 12^a. The lower head and foot braces 6 and 8 are connected together in a like manner by side-straining rods 13 and 13^a, which rods are located perpendicularly below and parallel to the upper rods 12 and 12^a. By reference to Fig. 4, it will be observed that the outer ends of the head and foot braces 5 6 7 and 8 are wedge or V-shaped, as at 14, which wedge shaped portions are adapted to fit in perpendicular wedge shaped grooves 15, formed on the inner faces of the corner posts 1 2 3 and 4, the object of which construction is to form a guidance for the said braces for purposes hereinafter described, and also to prevent the possibility of the braces being accidentally dislocated from their proper and relative positions. The top and bottom braces 5 and 6 and 7 and 8, respectively, are connected and held in parallel and spaced relation to each other by toggle links 16, 16^a and 17, 17^a, respectively. These toggle links are of the usual type of construction, each having a locking lip 18 to prevent the collapsing together of said links, in a manner easily comprehended, and thereby destroying the spaced relationship and parallelism of the respective sets of braces.
- 40 The braces 5 and 6 and 7 and 8, with the toggle links 16 16^a and 17 17^a, and the straining rods 12 12^a and 13 and 13^a form, when properly assembled as shown in Fig. 1, the stretching frame D for stretching or dis-
- 45 tending into proper tension the fabric of the bed bottom A and the sides B and C. I will now proceed to explain how this stretching process is accomplished, and first make reference to Fig. 5, which illustrates a cross section through the said stretching device when the same is in collapsed position. It will be observed that the supporting rods b and c have been passed through their respective bights or hems a along the upper edges of the sides B and C, and the fabric has been draped over or around the lower strain rods 13 and 13^a. Now, in assembling the bed, the corner posts 1 2 3 and 4 are first fitted to their respective ends of
- 50 the said supporting rods b and c, after which the head and foot braces of the stretching frame are entered in their respective wedge shaped grooves 15, and then the threaded rods 9 and 9^a are screwed into their proper positions, but, not so tightly, however, as to

prevent vertical movement of the head and foot braces. Reference to Figs. 2 and 3 will now disclose the fact that the fabric forming the bed side C drapes over the inner, upper portion of the periphery of the strain rod 12 and around the outer, lower quarter of the circumference of the rod 13. This same rule applies to that portion of the fabric which forms the side B, with respect to the upper and lower strain rods 12^a and 13^a, respectively. Assuming that the toggle links have been extended into the locked positions shown in Figs. 2 and 3, and the rods 9 and 9^a tightly screwed up, I proceed to stretch the bed fabric as follows: First stepping to the head of the bed, I loosen rod 9 with one hand, while with the other I press down heavily on brace 5 until the head portion of the bed has the desired tension, whereupon I tightly screw up said rod 9, so as to hold the braces 5 and 6 in rigid position. This operation is repeated at the foot of the bed, when it will be found that the bottom and sides of the bed fabric have been stretched or distended splendidly taut. I further stretch the bed bottom A by means of raw-hide or other lacing 20 and 19 threaded through slots 21 and 22 of the bottom head and foot braces 6 and 8, respectively, and through openings or gromets 23 24, located along the edges of the bottom A.

It will now be observed that all the natural stretch of the woven fabric due to atmospheric conditions or continued occupancy of the bed can be easily compensated for in my invention; attention is also called to the fact that my device as constructed produces a bed of a high degree of sanitation, being light and airy, with no obscure corners, lips, or projections to catch and retain dust or vermin; that it may readily be taken apart for cleaning, and that it may be put together by the veriest tyro.

It should now be understood that my invention carried out in its simplest form produces a splendid camp bed; constructed in smaller sizes, an ideal child's cradle is the result, while the suspended fabric bottom, coupled with a certain degree of elasticity and resiliency of the straining and supporting rods, makes it a most comfortable invalid's couch.

In the top edges of the top head and foot braces 5 and 7, medially of their length, are formed a pair of transverse notches 23^a and 24^a, for the reception of the ends of the supporting rods b and c when the bed is collapsed, as clearly shown in Fig. 4. When so collapsed, a reference to Fig. 5 will disclose the fact that there is between the folds of the fabric ample room for the four corner posts and the two rods 9 and 9^a, so that when the collapsed bed is carried about, all the component parts are contained in one package.

When my invention is used as a child's cradle, I employ a rocking device E, Fig. 6, comprising a flat, blade spring 30 at the free ends of which are supported the corner posts 5 of the head or foot of the bed, as the case may be. Said spring is fastened to a suitably shaped supporting block 31, and it is so proportioned that the slightest movement of the occupant of the cradle will set up a 10 vibration in the spring and impart a rocking motion to the cradle.

In manufacturing my invention, various types of construction may be employed. The various parts excepting the rods 9 and 15 9^a and the fabric may be produced from hard wood and finished as simply or ornately as desired. Or the parts may be made from tubing of the proper shape or 20 diameter, and either japanned or plated to suit the demands of the trade.

In the foregoing I have described the preferred mode of carrying out my invention, but I wish it distinctly understood that many changes in the details of construction 25 may be made without departing from said invention.

Having thus fully described this invention, I claim as new and desire to secure to the estate of the said NELSON CLEMENT by 30 Letters Patent of the United States, the following:—

1. A bed comprising head and foot members and connecting means therefor, an integral piece of fabric forming the sides and 35 bottom thereof, said fabric being supported from said connecting means, an independent fabric tensioning frame engaging said head and foot members, and said fabric, and adapted to maintain said fabric, in both 40 sides and bottom thereof, in positive tension, and means for maintaining said tensioning frame in fixed position.

2. A bed comprising an integral piece of 45 fabric forming the bottom and sides thereof, longitudinal supporting members at the upper edges of said sides, two pairs of corner posts, said members being removably fixed to said corner posts, and a collapsible fabric tensioning frame located between said posts 50 and adapted to maintain a positive tension in said fabric.

3. A bed comprising an integral piece of 55 fabric forming the bottom and sides thereof, longitudinal supporting members at the upper edges of said sides, two pairs of corner posts, said members being removably fixed to said corner posts, a collapsible fabric ten-

sioning frame located between said posts and adapted to maintain a positive tension in said fabric, and means for retaining said tensioning frame in fixed vertical position. 60

4. A bed comprising an integral piece of fabric forming the bottom and sides, longitudinal supporting rods at the upper edges 65 of said sides, pairs of head and foot corner posts supporting said longitudinal rods, transverse braces between said head and foot corner posts, rods connecting said braces, around which said fabric is draped to form said sides, and means located in said posts 70 whereby said braces are held in rigid position.

5. A bed comprising an integral piece of fabric forming the bottom and sides, longitudinal supporting rods at the upper edges 75 of said sides, pairs of head and foot corner posts supporting said longitudinal rods, collapsible transverse braces between said head and foot corner posts, rods connecting said 80 braces, around which said fabric is draped to form said sides, and means located in said posts whereby said braces are held in rigid position.

6. A bed comprising head and foot members and connecting means therefor, an integral piece of fabric forming the sides and bottom thereof, said fabric being supported from said connecting means, an independent fabric tensioning frame engaging said head and foot members, and said fabric, and 85 adapted to maintain said fabric, in both sides and bottom thereof, in positive tension, and means located in said head and foot members for maintaining said tensioning frame in fixed position. 90

7. A bed comprising head and foot members and connecting means therefor, an integral piece of fabric forming the sides and bottom thereof, said fabric being supported from said connecting means, an independent 100 fabric tensioning frame engaging said head and foot members, and being vertically adjustable therein, and means for maintaining said tensioning frame and said head and foot members in fixed, positive relationship. 105

In testimony whereof I have hereunto set my hand in the presence of two subscribing witnesses.

MARGARET CLEMENT,
Administratrix of the estate of Nelson Clement, deceased.

In the presence of—
J. K. MCMAHON,
EDWARD BARROWCLIFT.
